Geo. P. Himmel.
ATTORNEY.

UNITED STATES PATENT OFFICE.

THEODORE W. WATSON, OF PHOENIX, ARIZONA.

GARBAGE-RECEPTACLE STAND.

Application filed September 2, 1922. Serial No. 586,048.

To all whom it may concern:

Be it known that I, THEODORE W. WATSON, a citizen of the United States, residing at Phoenix, in the county of Maricopa and State of Arizona, have invented certain new and useful Improvements in Garbage-Receptacle Stands, of which the following is a specification.

This invention relates to holders or supports for receptacles, for instance, receptacles for garbage cans and like purposes, and has for one of its objects to improve the construction and increase the efficiency and utility of devices of this character.

Another object of the invention is to provide a device of this character, including a supporting frame having means whereby the cover of a receptacle which is supported in the frame is maintained in position above the receptacle to permit the latter to be tilted forwardly or removed from the supporting frame without removing the closure from the frame.

With these and other objects in view, the invention consists in certain novel features of construction as hereinafter shown and described and then specifically pointed out in the claim, and in the drawings illustrative of the preferred embodiment of the invention.

Figure 1 is a side elevation,

Fig. 2 is a front elevation,

Fig. 3 is a plan view of the supporting frame without the receptacle,

Fig. 4 is a side view, and

Fig. 5 is a plan view or a modified form of the receptacle cover.

Fig. 6 is a plan view of a modified construction of the receptacle support.

Fig. 7 is a section on the line 7—7 of Fig. 6.

Fig. 8 is a view similar to Fig. 6 illustrating another modification in the construction of the receptacle support.

Fig. 9 is a section on the line 9—9 of Fig. 8.

The improved device comprises an annular lower or base member 10 attached as at 11 to vertical side portions or standards 12 and 13, each preferably constructed of L metal with their confronting edges in spaced relation to form vertical guideways as shown in Fig. 2. One web of each of the members 13 is provided with a laterally directed recess, one of which is shown at 14.

Attached at its upturned ends at 15 to the

member 10 is a transverse support 16, and likewise attached by its upturned ends at 17 to the member 10 is another transverse member 18 at right angles to the member 16, 60 the two transverse members being riveted together where they cross as shown at 19.

The transverse member 16 is bent downwardly at its front end as shown at 20, to form a step to support the front of the 65 frame and likewise to form a cavity into which the forward edge of the receptacle 21 enters when tilted forwardly, as hereafter explained.

Attached by the rivet 15 at the rear side 70 of the member 10 and the upturned rear end of the transverse member 16, is another standard 22, the latter inclined rearwardly, as shown in Fig. 1.

The side members 12 and 13 and the rear member 22 extend below the lower line of the member 10 to form supporting feet which coact with the depression 20 to hold the member 10 and the transverse members 16 and 18 spaced above the ground or floor 80 on which the device rests.

At their upper ends the side members 12 and 13 and the rear member 22 are riveted or otherwise secured to a segmental member 23. 85

Extending inwardly from the rear standard 22 is a stop pin 24.

The receptacle is represented as a whole at 21 with a detachable closure or cover 26 having a downwardly directed rim 27. 90

Attached to the closure 26 is a handle 28 having laterally directed portions 29 extending through the guideways between the side members 12 and 13. The extensions 29 are each provided with notches 30 in their 95 side edges to receive the confronting edges of the webs of the members 12 and 13 to prevent lateral displacement of the closure 26.

When it is desired to place material in 100 the receptacle, or to discharge the contents of the same, the cover 26 is elevated bodily until the narrow section of the extensions 29 between the notches 30 is opposite recesses 14, when the closure will be moved 105 rearwardly to enter the narrow portions in the recess and the depending rim 27 above the stop pin 24, the recesses 14, extension 29 and pin 24, thus coacting to support the cover in horizontal position and spaced 110 above the upper open top of the receptacle, as shown by dotted lines in Figure 1.

When thus positioned, the receptacle is accessible for the deposit of material therein, or the receptacle can be readily tilted forwardly to enable it to be removed bodily 5 from the frame. When thus tilted, the forward edge of the receptacle enters the depression 20, and materially assists in the tilting action, as will be obvious.

The supporting frame can be constructed 10 of any suitable material and in any required size and can be adapted to receptacles of various sizes.

In Figs. 4 and 5 a modification in the construction of the closure 26 is shown, consisting 15 in forming the handle and the notch engaging projections in separate pieces, the handle being represented at 31 and the notch engaging member in the form of a continuous strap 32, extending transversely 20 of the closure, preferably at right angles to the handle 31, and attached to the closure as by rivets 33. The ends of the strap 32 extend beyond the closure and are provided with lateral notches 34 to enter the seats 25 14, the strap and its notches thus performing the same function as the extensions 29 and notches 30 shown in Figs. 1 and 2.

In Figs. 6 and 7 a modified construction 30 of the receptacle support is shown consisting in substituting for the transverse members 16 and 18, inwardly extending L-shaped supports 36, attached to the inner faces of the annular member 10 to support the receptacle 21.

In the modified structure the foot 20 is 35 replaced by an L-shaped foot 35, while the standard 22 is merged into another of the feet 35 while the remaining feet are attached to the legs 12, 13.

In Figs. 8 and 9 another modification of 40 the construction of the receptacle support is shown consisting in extending the lower

portions of the members 16 and 18 to form extended supports or feet 37.

The modifications do not constitute a 45 departure from the principle of the invention.

The preferred embodiment of the invention is disclosed in the drawings and set forth in the specifications, but it will be 50 understood that modifications within the scope of the claimed invention may be made in the construction without departing from the principle of the invention or sacrificing any of its advantages.

Having thus described the invention, what is claimed as new is:—

A device of the class described comprising a base formed of an annular member and transverse connecting members, one of said transverse members being depressed adjacent the front of the annular member, vertical side members and a vertical rear member rising from the base, said side members having longitudinally directed guideways with lateral recesses near the upper ends and said rear member having an inwardly directed stop, a receptacle adapted to bear on the transverse base members and extending over said depression and entering the same when the receptacle is tilted forwardly, a closure for the receptacle having laterally directed projections movably engaging said guideways, said projections adapted to enter said guideway recesses to dispose the cover in position to engage the stop and be supported thereby spaced above the receptacle, and permitting the same to be tilted for removal from the base without separating the closure from the support.

In testimony whereof, I affix my signature hereto.

THEODORE W. WATSON.
